Primary Examiner — Garth Rademaker*Assistant Examiner* — Melanie Pellegrini(74) *Attorney, Agent, or Firm* — Li & Cai Intellectual Property (USA) Office(57) **CLAIM**

The ornamental design for a ornament setting, as shown and described.

DESCRIPTION

FIG. 1 is a perspective view of an ornament setting showing my new design;

FIG. 2 is a front view thereof;

FIG. 3 is a rear view thereof;

FIG. 4 is a left side view thereof, the right side view being a mirror image thereto;

FIG. 5 is a top view thereof;

FIG. 6 is a bottom view thereof;

FIG. 7 is a perspective view showing the practical usage thereof;

FIG. 8 is another perspective view showing the practical usage thereof; and,

FIG. 9 is the other perspective view showing the practical usage thereof.

The broken lines depict environmental subject matter only and form no part of the claimed design.
